CIRCUIT BREAKER WITH BLAST VALVE
MOTOR ASSISTING THE CONTACT MOTOR

Ira W. Paterson, Milton, Mass., assignor to Allis-Chalmers Manufacturing Company, Milwaukee, Wis., a corporation of Delaware

Application August 17, 1949, Serial No. 110,686

11 Claims. (Cl. 200—82)

1

This invention relates to electric circuit breakers, and more particularly to operating mechanisms for electric circuit breakers of the fluid operated type. Specifically, this invention is an improvement on the circuit breaker operating mechanism disclosed and claimed in C. D. Ainsworth's application Serial No. 119,284, filed October 3, 1949.

A pneumatic or fluid operated mechanism for an electric circuit breaker should provide controlled opening forces that produce a high initial acceleration for rapidly separating the arcing contacts. It is desirable, however, to increase the opening speed by some method other than the method which increases the opening speed by virtue of the fluid blast acting on the movable contacts within the arc chutes.

Many types of circuit breaker systems have used a fluid motor for actuating the arcing contacts. This fluid motor was usually controlled by a valve which caused actuation of the contact actuating fluid motor in a predetermined sequence with other circuit breaker control equipment. Operating mechanism of this type, however, requires a relatively large initial force in order to rapidly separate the relatively movable arcing contacts, which are usually in frictional engagement.

In accordance with the invention claimed, a new and improved operating mechanism involving two fluid motors, is provided to rapidly separate a pair of cooperating arcing contacts in an electric circuit breaker. The first motor, which actuates a blast valve to valve open position, is connected with the second motor, which actuates the arcing contacts of the circuit breaker, so as to boost the action of the second motor, thereby effectively utilizing more completely the total energy of the first motor upon blast valve actuation. More particularly, the first motor actuates a differential type blast valve to control a supply valve to the pneumatic contact actuating motor and boosts the action of the pneumatic contact actuating motor, thereby increasing the speed of contact separation. This improved arrangement provides an operating mechanism which increases the opening speed of the circuit breaker system.

It is therefore one object of the present invention to provide a new and improved pneumatic operating mechanism for circuit breakers of the fluid blast type.

Another object of the present invention is to provide a new and improved fluid operating mechanism for electric circuit breakers which provides controlled pneumatic opening forces which pro-

2

duce a high initial acceleration for rapidly separating the arcing contacts.

A further object of the present invention is to provide a new and improved arrangement for two fluid motors in which one motor boosts the action of the other motor.

A still further object of the present invention is to provide a new and improved arrangement for two sequentially operated fluid motors in which one motor boosts the action of the second motor in a predetermined sequence.

A still further object of the present invention is to provide a new and improved pneumatic operating mechanism for actuating a fluid blast electric circuit breaker in which the actuating force of a blast valve boosts the action of a pneumatic contact actuating motor to rapidly separate a pair of cooperating arcing contacts.

Objects and advantages other than those set forth will be apparent from the following description when read in connection with the accompanying drawing in which the single figure is a diagrammatic showing of a circuit breaker and a pneumatic operating mechanism therefor embodying the present invention.

Referring more particularly to the drawing by characters of reference, the figure illustrates a circuit breaker including as a constructive element thereof a reservoir 6 constituting a source of supply of fluid under pressure, which will be assumed herein to be compressed air, supplied from a suitable compressor (not shown). Although in general, circuit breakers of the type herein considered are provided with a plurality of similar pole structures, one for each phase of a polyphase electric circuit, only one such pole structure or pole unit is shown in the figure and the circuit breaker will be described in detail as if it were of the single pole type.

The circuit breaker comprises a fixed arcing contact 7 and a cooperating movable arcing contact 8 connected in an electric circuit through terminal studs 9 and 10. The arcing contacts are mounted to engage within an arcing chamber 11 which is aligned with an arc chute 12. The arcing chamber 11 is axially aligned with a hollow insulator 13 which provides a connection between reservoir 6 and arcing chamber 11 through a suitable blast valve 14 for the purpose of directing a blast of arc extinguishing fluid under pressure between the arcing contacts and through the arcing chamber 11.

The differential type blast valve 14 comprises fluid motors 16 and 17 for controlling a blast inlet port 18. Motor 16 comprises a cylinder 20, a pis-

ton 21, a piston rod 22, a spring 23, and an inlet port 24. Motor 17 comprises a cylinder 25, a piston 26, a return spring 27 for piston 26, a vent 28, and an exhaust port 29. Valve 31 for closing an exhaust port 32 is adapted to be operated by motor 17. Cylinder 33 cooperates with cylinder 25 of motor 17 to provide an exhaust port 34. Piston 26, when actuated by air under pressure actuates valve 31 and opens exhaust port 32 against the action of spring 27. As long as exhaust port 32 remains closed, air under pressure supplied from reservoir 6 through inlet port 24 cooperates with spring 23 to maintain piston 21 in the position shown.

Inlet port 35 of blast valve 14 supplies fluid motor 17 with operating fluid under pressure for actuating piston 26. Inlet port 35, however, is controlled by a slide valve 15 provided with a piston 19 which opens and closes port 35 upon predetermined circuit conditions.

A solenoid type control valve 36 controls the opening of blast valve 14 upon the occurrence of a predetermined electrical condition of the electric circuit controlled. Control valve 36 may be of any suitable known type and is diagrammatically shown as a valve of the magnetic type. Pipes 44 and 45 connect valve 36 to differential type blast valves associated with other phase structures of the circuit breaker. Pipe 45 connects valve 36 to reservoir 6.

The movable arcing contact 8 is actuated by a fluid motor 47 through the medium of a crank-shaft 48, a pair of cranks 51, 52, and a connecting rod 53. Fluid motor 47 comprises a cylinder 54, a piston 55, a hollow piston rod 56 movable with piston 55 and connected through a link 57 to crank 51, ports 59, 60, a pair of control valves 58, 61 for ports 62, 63, respectively, springs 64, 65 for biasing control valves 58, 61, respectively, to their closed positions, valves 66, 67, and springs 68, 71 for biasing valves 66, 67, respectively, to their closed positions. Piston rod 56 is provided with a plurality of exhaust ports 72, 73 for exhausting pressure from the ends of the cylinder. A pipe line 69 connects port 70 of motor 47 to slide valve 15.

The contact actuating fluid motor 47 is controlled by a valve 75 which regulates the time at which fluid under pressure is supplied from reservoir 6 through a pipe line 76 to motor 47. Valve 75 comprises a valve element 82 forming a valve stem 83, a biasing spring 84 and ports 85, 86, 89 and 90. Spring 84 biases valve element 82 in valve closing direction, thus closing port 85 and prohibiting the passage of air from pipe line 76 through port 89, valve 75 and port 90 to air inlet port 60 of motor 47. As illustrated in the drawing valve 75 may be mounted immediately adjacent motor 47 with port 90 of valve 75 and port 60 of motor 47 interconnected.

Valve 75 is connected by means of port 86 and pipe line 87 to an inlet port 88 of trip predominating valve 77. Trip predominating valve 77 further comprises a cylinder 91, piston 92, valve element 93, spring 94, an inlet port 96 which is connected to a suitable solenoid type closing control valve 97 and a port 99 which interconnects with a port 78 of cylinder 54. Control valve 97 is connected to reservoir 6 through pipe line 98.

A means such as a mechanical interconnecting rod and lever arrangement is provided for actuating control valve 75 upon actuation of piston 21 and piston rod 22 of motor 16. This interconnecting rod and lever arrangement comprises a lever 101 pivoted at a point 102 with one end

thereof connected at a point 103 to piston rod 22 and the other end connected to one end of a connecting rod 104. The other end of connecting rod 104 is pivotally secured to a crank 105 which oscillates with a shaft 106 through a given arcuate path. A second crank 107 mounted on shaft 106 and provided to oscillate through a given arcuate path therewith, actuates valve stem 83 of control valve 75 upon clockwise movement thereof. Fluid motor 16 controls fluid motor 47 through the medium of control valve 75 and thus provides for rapid sequential operation thereof.

A pneumatic brake 108 comprising brake shoes 111 acting on a drum 112 connected to shaft 43 is provided for arresting the movement of shaft 48 at a predetermined time to lessen the impact of the moving mass of the movable contact assembly. Piston 55 controls the supply of air from cylinder 54 of motor 47 through a pipe 114 to a cylinder 116 provided with a piston 115. The cylinder and the piston are connected to brake shoes 111 to produce the retarding action.

In accordance with the invention claimed a mechanical interlocking or booster means 117 is provided for boosting the action of the pneumatic contact actuating motor 47. Booster means 117 comprises a lever arm 118 secured to shaft 106 and a cooperating lever arm 119 secured to crankshaft 48. Upon clockwise actuation of shaft 106, lever arm 118 engages a surface 120 on lever arm 119 and rotates lever arm 119 and crankshaft 48 counterclockwise.

The circuit breaker illustrated in the drawing is shown with the cooperating arcing contacts in the closed circuit position and the pneumatic operating mechanism in the corresponding position. An opening operation is initiated by energization of the tripping solenoid control valve 36, thereby causing air under pressure from reservoir 6 to pass through pipe 46 to and through valve 36, valve 15 through port 35 to the fluid motor 17 and through pipes 44 and 45 to any similar motor associated with other phase structure of the circuit breakers. Air under pressure causes piston 26 of motor 17 to move against the action of spring 27 and to actuate valve 31, thus opening port 32 which exhausts the air under pressure trapped in cylinder 20 through ports 34. This exhausting action reduces the pressure behind piston 21 of fluid motor 16 and enables the air under pressure in reservoir 6 acting on the portion of the top side of piston 21 surrounding the seat of the blast valve to overcome the action of spring 23. A blast of air under pressure then passes through the hollow insulator 13, through the arcing chamber 11 and into the arc chute 12.

Upon the actuation of piston 21 of fluid motor 16 in blast valve opening direction, piston rod 22 of fluid motor 16 rotates lever 101 counterclockwise which in turn actuates connecting rod 104 to rotate crank 105 and shaft 106 clockwise. Clockwise rotation of shaft 106 causes actuation of shaft 83 of control valve 75 in valve opening direction, thus causing air under pressure from reservoir 6 to flow through pipe line 76, to and through valve 75, through port 60 and into cylinder 54 of contact actuating fluid motor 47 and into pipe 69. Air under pressure in the contact opening end of cylinder 54 passes through ports 62 and overcomes the bias of spring 64 to open control valve 58 and actuate piston 55 in contact opening direction. Upon movement of piston 55 in contact opening direction, piston rod 56 of fluid motor 47 rotates crank 51, shaft 48, and

crank 52 counterclockwise, thus actuating connecting rod 53 to separate the arcing contacts 7, 8. Movement of piston 55 in contact separating direction opens port 59, and air under pressure flows through pipe 114 to cylinder 116 of brake 108. Movement of piston 115 under the action of air under pressure applies the shoes of brake 108 to retard the movement of the moving arcing contact 8.

Blast valve 14 is actuated to valve open position by reducing the pressure behind piston 21 of fluid motor 16, thereby enabling the air under pressure in reservoir 6 acting on the portion of the top side of piston 21 surrounding the seat of the blast valve to exert a first actuating force to overcome the action of spring 23. Upon cracking of blast valve 14, i. e., the initial movement of piston 21 in valve opening direction, the air under pressure in reservoir 6 acts on the total area of piston 21 and creates a force much greater than that needed to rapidly move piston 21 to the bottom of cylinder 20. The second actuating force, inherent in the blast valve operation, which results from the air pressure on the portion of piston 21 serving to open port 18, is available for contact actuation, but heretofore has been wasted as excess energy. In order to utilize this excess energy a new and improved booster means is provided to harness the excess energy of the blast valve for aiding the contact actuating motor to more rapidly separate the arcing contacts, thus providing a faster and more efficient circuit breaker operating mechanism. By utilizing the excess energy of the blast valve 14, the contact actuating motor 47 may be reduced in size and weight, thereby permitting a lighter and faster operating pneumatic mechanism for circuit breaker operation.

Upon actuation of blast valve 14 in valve opening direction to the extent necessary to enable the blast pressure to be exerted on the entire area of piston 21 and the resulting clockwise rotation of shaft 106, lever arm 118 engages surface 120 of lever arm 119 and boosts the contact actuating motion of fluid motor 47 by also rotating crank shaft 48 under the action of the excess force available at piston 21. The high initial acceleration of blast valve 14 produces a hammer blow by lever arm 117 on the engaging surface 120 of lever arm 119 a predetermined time after the blast valve is set in motion, thus boosting the action of motor 47 and quickly separating the arcing contacts. This booster action of blast valve 14, which may be exerted over the entire stroke of piston 55 or over only part of such stroke, decreases the time necessary for contact separation as evidenced from the following data recorded on the operation of a cross air blast circuit breaker before and after this invention was added to the operating mechanism of the circuit breaker system.

Before

At 150 lbs. p. s. i. operating pressure the arcing contacts parted in 4.2 cycles and were fully opened in 10.2 cycles.

At 200 lbs. p. s. i. operating pressure the contacts parted in 3.8 cycles and were fully open in 9.3 cycles.

After

At 150 lbs. p. s. i. operating pressure the contacts parted in 3.6 cycles and were fully opened in 8.5 cycles.

At 200 lbs. p. s. i. operating pressure the contacts parted in 3.3 cycles and were fully opened in 7.75 cycles.

tacts parted in 3.3 cycles and were fully opened in 7.75 cycles.

Ports 72, 73 are provided in the hollow piston rod 56 of motor 47 for exhausting the air under pressure that might be trapped in the cylinder 54 on the trailing side of piston 55 at the end of its stroke, thus permitting rapid reversal motor action. In addition, valves 66, 67 are so designed to overcome the biasing action of their respective springs 68, 71 to permit rapid exhausting of the air under pressure on the leading side of piston 55.

In order to conserve air under pressure in reservoir 6 and to rapidly close the blast valve at a given predetermined time, air under pressure in pipe line 69 actuates piston 19 thus closing the air inlet port 35 to blast valve 14 and any other blast valves of the circuit breaker. The pressure on piston 26 of motor 17 is relieved by exhaust port 29, and spring 27 biases piston 26 to the position shown. Any air under pressure having leaked past piston 26 is exhausted through vent 28. The movement of piston 26 under the action of spring 27 lowers valve 31 against its valve seat and permits a back pressure to build up under piston 21 such that in combination with the biasing action of spring 23 returns piston 21 to the position shown, thus closing blast valve 14.

A closing operation is initiated by energization of the closing solenoid control valve 97, thereby causing air under pressure from reservoir 6 to pass through valve 97, port 96 of valve 77, valve 77, port 78 of cylinder 54, and into the closing end of fluid motor 47. The air further flows through ports 63, opens valve 67 against the biasing effect of spring 65 and actuates piston 55 of fluid motor 47 in contact closing direction, thus closing the arcing contacts.

If opening and closing impulses are substantially simultaneously initiated by valves 36 and 97, respectively, air under pressure from pipe line 76 flows through control valve 75, port 86 of valve 75, pipe 87, inlet port 88 of trip predominating valve 77 and actuates piston 92 thereof upward, thus actuating valve element 93 to close port 99 in cylinder 91. Closing air from valve 97 is, thus, restrained from reaching cylinder 54 through port 99 of trip predominating valve 77 and port 78 of fluid motor 47 to close the arcing contacts. Once valve element 93 is actuated to closed position, no contact closing pressure impulse can be passed through valve 77 as long as closing solenoid valve 97 remains open since valve 97 feeds air to the chamber below valve element 93 thereby holding valve element 93 in closed position. As long as the blast valve remains open, air is supplied under piston 92 through valve 75, which action also holds valve element 93 in closed position.

Although but one embodiment of the present invention has been illustrated and described, it will be apparent to those skilled in the art that various changes and modifications may be made therein without departing from the spirit of the invention or from the scope of the appended claims.

It is claimed and desired to secure by Letters Patent:

1. In combination: a first device, a first fluid operated motor for actuating said first device, a second device, a second fluid operated motor for actuating said second device, a valve for admitting fluid under pressure to said second motor, mechanical means actuated by said first motor

for actuating said valve, and mechanical means actuated by said first motor for actuating said second device in common with said second motor.

2. In combination: a first device, a first fluid operated motor for actuating said first device, a second device, a second fluid operated motor for actuating said second device, a valve for admitting fluid under pressure to said second motor, mechanical means actuated by said first motor for actuating said valve, and booster means actuated by said first motor for aiding said second motor to actuate said second device.

3. In combination: a first device, a first fluid operated motor comprising a cylinder and a piston for actuating said first device, a second device provided to operate in sequence with said first device, a second fluid operated motor comprising a cylinder and a piston for actuating said second device, a source of fluid under pressure, valve means for controlling the time at which fluid under pressure is supplied to said second motor, means interconnecting said first device and said valve means for actuating said valve means upon actuation of said piston of said first motor, and booster means actuated by said first motor for aiding said second motor to actuate said second device.

4. In an interlocking system for two fluid operated motors intended to operate in sequence, the combination comprising: a first device, a first fluid operated motor for actuating said first device, a second device, a second fluid operated motor for actuating said second device, a source of fluid under pressure, a valve for admitting fluid under pressure to said second motor, mechanical means operated by said first motor for actuating said valve, and booster means actuated by said first motor for aiding said second motor to actuate said second device, said booster means and said second motor acting on said second device in a predetermined sequence.

5. In a fluid blast circuit interrupter, the combination comprising: a source of fluid under pressure, separable arcing contacts for establishing an arc, a blast valve arranged to provide a blast of fluid under pressure from said source for extinguishing the arc drawn upon separation of said arcing contacts, a first fluid operated motor comprising a cylinder and a piston for actuating said blast valve, a second fluid operated motor arranged to operate in sequence with said blast valve comprising a cylinder and a piston for separating said arcing contacts, valve means for controlling the time at which fluid under pressure is supplied to said second motor, mechanical means interconnecting said valve means and said piston of said first motor for actuating said valve means upon actuation of said first motor, and booster means actuated by said first motor for aiding said second motor to actuate said arcing contacts, said booster means and said second motor acting on said arcing contacts in a predetermined sequence.

6. In a fluid blast circuit interrupter, the combination comprising: a source of fluid under pressure, separable arcing contacts for establishing an arc, a blast valve arranged to provide a blast of fluid under pressure from said source for extinguishing the arc drawn upon separation of said arcing contacts, a first fluid operated motor comprising a cylinder and a piston for actuating said blast valve, a second fluid operated motor arranged to operate in sequence with said blast valve comprising a cylinder and a piston for separating said arcing contacts, means ar-

ranged immediately adjacent said second motor for controlling the time at which fluid under pressure is supplied from said source to said second motor and comprising a valve adapted to be actuated by said piston of said first motor, and booster means actuated by said first motor for aiding said second motor to actuate said arcing contacts, said booster means and said second motor acting on said arcing contacts in a predetermined sequence.

7. In a fluid blast circuit interrupter, the combination comprising: a source of fluid under pressure, separable arcing contacts for establishing an arc, a blast valve arranged to provide a blast of fluid under pressure from said source for extinguishing the arc drawn upon separation of said arcing contacts, a first fluid operated motor comprising a cylinder and a piston for actuating said blast valve, a second fluid operated motor arranged to operate in sequence with said blast valve comprising a cylinder and a piston for separating said arcing contacts, valve means for controlling the time at which fluid under pressure is supplied to said second motor, mechanical means interconnecting said valve means and said piston of said first motor for actuating said valve means upon actuation of said first motor, and booster means actuated by said first motor for actuating said arcing contacts in common with said second motor.

8. In a fluid blast circuit interrupter the combination comprising: a source of fluid under pressure, separable arcing contacts for establishing an arc, a blast valve arranged to provide a blast of fluid under pressure from said source for extinguishing the arc drawn upon separation of said arcing contacts, a first fluid operated motor comprising a cylinder and a piston for actuating said blast valve, a second fluid operated motor arranged to operate in sequence with said blast valve comprising a cylinder and a piston for separating said arcing contacts, valve means for controlling the time at which fluid under pressure is supplied to said second motor, mechanical means interconnecting said valve means and said piston of said first motor for actuating said valve means upon actuation of said first motor, and booster means for actuating said arcing contacts by said first motor in common with said second motor upon admission by said valve of fluid under pressure to said second motor.

9. In a fluid blast circuit interrupter, the combination comprising: a source of fluid under pressure, separable arcing contacts for establishing an arc, a blast valve arranged to provide a blast of fluid under pressure from said source for extinguishing the arc drawn upon separation of said arcing contacts, a first fluid operated motor comprising a cylinder and a piston for providing first and second actuating forces, said first force actuating said blast valve to valve open position, a second fluid operated motor arranged to operate in sequence with said blast valve comprising a cylinder and a piston for separating said arcing contacts, valve means for controlling the time at which fluid under pressure is supplied to said second motor, mechanical means interconnecting said valve means and said piston of said first motor for actuating said valve means upon actuation of said first motor, and booster means actuated by said second force of said first motor for aiding said second motor to actuate said arcing contacts, said booster means and said second motor acting on said arcing contacts in a predetermined sequence.

10. In a fluid blast circuit interrupter, the combination comprising: a source of fluid under pressure, separable arcing contacts for establishing an arc, a blast valve arranged to provide a blast of fluid under pressure from said source for extinguishing the arc drawn upon separation of said arcing contacts, a first fluid operated motor comprising a cylinder and a piston for providing first and second sequential actuating forces, said first force actuating said blast valve to valve open position, a second fluid operated motor arranged to operate in sequence with said blast valve comprising a cylinder and a piston for separating said arcing contacts, valve means for controlling the time at which fluid under pressure is supplied to said second motor, mechanical means interconnecting said valve means and said piston of said first motor for actuating said valve means upon actuation of said first motor, and booster means actuated by said second force of said first motor a predetermined time after the initial actuation of said blast valve for aiding said second motor to actuate said arcing contacts, said booster means and said second motor acting on said arcing contacts in a predetermined sequence.

11. In a fluid blast circuit interrupter, the combination comprising: a source of fluid under pressure, separable arcing contacts for establishing an arc, a blast valve arranged to provide a

20

25

30

blast of fluid under pressure from said source for extinguishing the arc drawn upon separation of said arcing contacts, a first fluid operated motor comprising a cylinder and a piston for providing a first and a second sequential actuating force, said first force actuating said blast valve to valve open position, a second fluid operated motor comprising a cylinder and a piston for separating said arcing contacts, valve means for controlling the time at which fluid under pressure is supplied to said second motor, mechanical means interconnecting said valve means with said piston of said first motor for actuating said valve means upon actuation of said first motor, and booster means actuated by said second force of said first motor a predetermined time after the initial actuation of said first motor for aiding said second motor to actuate said arcing contacts.
